UNITED STATES PATENT OFFICE.

AUGUSTUS P. DAVIS, OF PITTSBURG, PENNSYLVANIA.

DESIGN FOR A CAMP-SEAL.

SPECIFICATION forming part of Design No. 17,954, dated December 20, 1887.

Application filed November 14, 1887. Serial No. 255,168. Term of patent 7 years.

To all whom it may concern:

Be it known that I, AUGUSTUS P. DAVIS, a citizen of the United States, residing at Pittsburg, in the county of Allegheny, State of Pennsylvania, have invented and produced a new and original Design for a Camp Seal, of which the following is a full description and specification, reference being had to the accompanying drawing, forming a part thereof.

10 The figure is a front view of my newly-designed seal.

In the center and on the face of the seal is the representation of an American eagle seated on a pile of rocks and surrounded by stars, 15 the said pile of rocks resting on a roll composed of equal parts. Above the eagle appears an ornamental scroll containing within

its upper and lower lines a space for an inscription. Below the roll is another vacant space, also reserved for an inscription. Surrounding the said eagle and all of the foregoing named rocks, stars, roll, scroll, and vacant spaces are two concentric circles, also containing between the outer and inner lines of the circles a space for an inscription. 20 25

What I claim is—

The design for a seal, consisting of the eagle, the pile of rocks, the stars, the roll, the ornamental scroll, and the two concentric circles, as set forth and shown.

AUGUSTUS P. DAVIS.

Witnesses:

H. A. DAVIS,
FRANK G. WAGGONER.
